UNITED STATES PATENT OFFICE.

PETER SHINKLE, OF COVINGTON, KENTUCKY.

COMMODE.

SPECIFICATION forming part of Letters Patent No. 225,649, dated March 16, 1880.

Application filed January 26, 1880.

To all whom it may concern:

Be it known that I, PETER SHINKLE, of Covington, in the county of Kenton and State of Kentucky, have invented a new and useful Improvement in Commodes, which improvement is fully set forth in the following specification and accompanying drawing, in which the figure is a side sectional view.

The object of my invention is to provide a simple and cheap commode for use in sick-rooms or otherwise, and so constructed that it is ornamental in appearance.

In the drawing, A A represents the sides or ends of the box forming the main body of the commode, having a bottom, B. The box thus constructed is mounted on rollers C, within the box, midway between the bottom and the top. Cleats D are secured to the sides A, upon which the floor E, covering two-thirds or more of the interior space, is placed. Upon this floor E the chamber H is placed.

The lid F, hinged to the rear side of the box and provided with a suitable orifice centrally, rests on cleats G, secured around the inner surface of the box A.

Any number of cleats D at different heights may be secured to the interior of the box, the object being to so arrange them as to bring the upper edge of the chamber H flush with the lower surface of the lid F.

The top I is hinged to the rear side of the

box A, and has a rear beveled projection, I', which rests against the upright of the box when thrown back, thus keeping the top I in an erect position, to be used as a back-rest for 35 the person using the commode.

A flange, J, around the entire edge of the top I, projects downward, and is made to fit closely to the box A, so that when the top I is closed down there will be no danger of any 40 scent arising from the chamber within. The top I is then suitably upholstered, as shown, thus presenting the appearance of a common upholstered stool or divan.

E represents a guard for the chamber H. 45

Having described my invention, what I claim as new, and desire to secure by Letters Patent, is—

The combination of the box A, having cleats D G, floor E, lid F, and chamber H, with the 50 upholstered top I, having beveled part I', and flange J, substantially as and for the purpose herein set forth.

In testimony that I claim the foregoing I have hereunto subscribed my hand this 21st 55 day of January, 1880, in the presence of witnesses.

PETER SHINKLE.
